(57) **CLAIM**

The ornamental design for agricultural machine driving apparatus, as shown and described.

DESCRIPTION

FIG. 1 is a front, left, top perspective view of a first embodiment of an agricultural machine driving apparatus showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a reference perspective view thereof;

FIG. 9 is a reference perspective view thereof;

FIG. 10 is a front, left, top perspective view of a second embodiment of an agricultural machine driving apparatus showing our new design;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom view thereof;

FIG. 17 is a reference perspective view thereof; and,

FIG. 18 is a reference perspective view thereof.

The broken lines represent the portions of the design that form no part of the claim.
